UNITED STATES PATENT OFFICE.

GEORGE LARGE, OF PORT WASHINGTON, WISCONSIN, ASSIGNOR TO GILSON MANUFACTURING COMPANY, OF PORT WASHINGTON, WISCONSIN.

FUEL-PUMP FOR INTERNAL-COMBUSTION ENGINES.

1,393,551.

Specification of Letters Patent.

Patented Oct. 11, 1921.

Application filed November 17, 1919. Serial No. 338,541.

To all whom it may concern:

Be it known that I, GEORGE LARGE, a citizen of the United States, and resident of Port Washington, in the county of Ozaukee and State of Wisconsin, have invented certain new and useful Improvements in Fuel-Pumps for Internal-Combustion Engines; and I do hereby declare that the following is a full, clear, and exact description thereof.

10 My invention relates to new and useful improvement in pumps, more particularly of the type adapted for association with heavy duty internal combustion engines for pumping oil or other fuel from the main 15 supply reservoir to the carbureter of the engine.

Pumps of this nature have heretofore required drive mechanism independent of the engine gear for procuring the necessary reciprocating movements of their plungers.

It is primarily the object of my invention to simplify the general structure of engines of the foregoing type by eliminating independent drive mechanism for the fuel pump, 25 and it is more particularly my object to utilize the reciprocating movement of the tappet valve mechanism of the engine in procuring operation of the pump.

A further object resides in the provision 30 of an exceedingly simple and effective pump mechanism adapted for operation in the aforescribed manner.

With the above and other objects and advantages in view, which will be apparent 35 as the description proceeds, my invention resides in the novel features of construction, combination and arrangement of the parts as hereinafter described and defined by the appended claims.

40 In the accompanying drawings:

Figure 1 is a plan view of my improved pump structure associated with the cylinder head end portion of an internal combustion engine, the cylinder being shown in section.

45 Fig. 2 is a sectional view through the pump on a plane indicated by the line 2-2 of Fig. 1.

Referring now more particularly to the accompanying drawings, 5 designates the cylinder of an internal combustion engine which is closed by the end head 6 having formed therein the usual inlet and outlet ports 7 and 8 respectively. The inlet port is controlled by a spring valve 9 carried on 55 a stem 10 extending through the cylinder

head and resiliently urged to closing position by a spring 11. The outlet port 8 is controlled by the usual tappet valve 12 carried on a stem 13 slidable in the cylinder head and resiliently urged to closing position by a relatively strong spring 14, the valve being open at the proper time incidental to operation of the engine by a tappet lever 15 intermediately pivoted on an arm 16 outstanding from the cylinder head, 60 one end of the lever being engageable with the headed out end of the valve stem 13 while the other end of the lever is connected with the usual tappet rod 17 which is reciprocated by a valve cam (not shown). 70

My improved pump mechanism associated with this engine structure includes a vertical pump chamber formed by the hollow cross portion 18 of a T-shaped casting. The shank 19 of said casting carries an attaching arm 20 secured by bolts 21 to the pivot arm of the pump lever, the shank being thus mounted to extend toward the tappet lever 15. The end portions of the bore of the cross piece 18 are counter-sunk to receive 80 upper and lower connecting nipples 22 and 23 adapted for connection respectively with pipes (not shown) leading to the engine carbureter and to a suitable main fuel reservoir. Annular valve seating shoulders 24 85 are formed at the inner ends of the counter-sunk portions of the cross piece and balls 25 are disposed in the counter-sunk portions, the upper ball normally resting against the corresponding valve seat 24 while the lower 99 ball normally rests on and closes the nipple 23, the other valve seat 24 being idle and merely affording a reversible nature to the pump casting. A piston plunger is slidable in the shank 19 of the casting, a suitable 95 packing gland 27 being disposed about the plunger at the outer end of the shank. The outer end of the plunger is disposed between a pair of pivot ears 28 on the adjacent portion of the tappet lever 15 and is connected 100 therewith by pin 29, there being sufficient looseness of parts to compensate for the ar- cuate rocking movement of the lever end. In operation the piston plunger is thus 105 reciprocated upon each reciprocation of the tappet mechanism incidental to the operation of the engine whereby to draw oil or other fuel liquid from the nipple 23 and discharge the same through the nipple 22 to the carbureter, the capacity of the pump be- 110

ing so proportioned with respect to the reciprocative movement of the tappet mechanism as to supply an adequate amount of fuel liquid to the carbureter under normal running conditions of the engine.

An efficient and exceedingly simple arrangement is thus provided which eliminates the necessity of independent driving mechanism for the fuel pump of the engine 10 and which conduces to the provision of an exceedingly compact and simple engine structure.

While I have shown and described a preferred form of my invention, it will be appreciated that various changes and modifications of structure and arrangement of parts may be employed to meet differing conditions of use and manufacture without departing in any manner from the spirit of 20 my invention which resides in the utilization of the tappet valve mechanism to procure direct driving action of the fuel pump.

What is claimed is:

1. In an internal combustion engine, the 25 combination with a cylinder head of a tappet valve including a stem projecting from the cylinder head, a pivot arm on the cylinder head, a tappet lever intermediately piv-

oted on said arm and having one end engageable with the valve stem, means pivoted to the opposite end of the lever for actuating the same, fuel pump including a 30 casing, an arm supporting the casing and secured to said pivot arm, and a piston plunger extending into the pump casing and 35 pivotally connecting it with the tappet lever between its fulcrum and the actuating means.

2. The combination with a cylinder head 40 of an internal combustion engine, of a tappet valve including a stem projecting from said cylinder head, a tappet lever fulcrumed intermediate its ends and having an abutment carried at one end engageable with the valve stem, a fuel pump including a 45 casing and a plunger reciprocable within the casing, said plunger having a stem pivotally connected with said tappet lever on the opposite side of its fulcrum from said 50 abutment.

In testimony that I claim the foregoing I have hereunto set my hand at Port Washington, in the county of Ozaukee and State of Wisconsin.

GEORGE LARGE.
